Primary Examiner — Derrick Holland*Assistant Examiner* — Jennifer O King(74) *Attorney, Agent, or Firm* — Michael Best & Friedrich LLP(57) **CLAIM**

I claim the ornamental design for a generator enclosure, as shown and described.

DESCRIPTION

FIG. 1 is a front view of a generator enclosure; FIG. 2 is a front perspective view thereof.

The broken lines shown represent unclaimed subject matter and form no part of the claimed design.

1 Claim, 2 Drawing Sheets(56)
